UNITED STATES PATENT OFFICE.

ELIHU THOMSON, OF SWAMPSCOTT, MASSACHUSETTS, ASSIGNOR TO
GENERAL ELECTRIC COMPANY, A CORPORATION OF NEW YORK.

VAPOR-BURNER.

SPECIFICATION forming part of Letters Patent No. 792,562, dated June 13, 1905.

Original application filed May 24, 1900, Serial No. 17,806. Divided and this application filed June 21, 1901. Serial No. 65,520½.

To all whom it may concern:

Be it known that I, ELIHU THOMSON, a citizen of the United States, residing at Swampscott, in the county of Essex and State of Massachusetts, have invented certain new and useful Improvements in Vapor-Burners, of which the following is a specification.

This application is a division of my pending application, Serial No. 17,806, filed May 24, 1900, on thermo-regulators for vapor-burners, which division is made in accordance with the requirements of the United States Patent Office under the provisions of Rules Nos. 41 and 42.

15 The invention relates to vapor-burners, and has for its object to provide a burner which can be automatically regulated in accordance with the demand made on the boiler for steam.

20 The invention further consists in certain improvements in burner construction, which will be more fully described and claimed hereinafter.

25 In the accompanying drawings, which illustrate my invention, Figure 1 is a longitudinal section of a boiler and burner. Fig. 2 is a plan view of the same with certain of the parts in section, the section being taken on a line 2 2 of Fig. 1; and Fig. 3 is a cross-section of the main burner.

30 The boiler is composed of two metal cylinders A and B. The former cylinder surrounds the latter and is arranged concentrically therewith. On the periphery of the cylinder B is formed a spiral groove C, which 35 constitutes a part of the water-passage of a flash-boiler, the other part being formed by the outer cylinder A, which fits tightly over the inner cylinder. Projecting inwardly from the inner wall of the cylinder B and outwardly 40 from the periphery of the cylinder A are small projections D, which serve to baffle the flames, absorb the heat, and transmit it to the water or steam in the passage C. Mounted within the cylinder B and engaging with the 45 projections thereon is a cylinder E of a refractory material, such as fire-brick. The end of the cylinder next the burners is closed by a disk E' of heat-resisting material, so that the products of combustion are compelled to

50 pass through the spaces between the projections D on their way to the rear chamber F. The entire boiler is surrounded by a casing G, made of fire-brick or other similar material, which is extended at the right-hand end to form a chamber for the main burner H and 55 the auxiliary burner I and at the other end to form a chamber F for the waste products of combustion. Connecting with the last-mentioned chamber and extending over the boiler is a long flaring funnel or chimney J, having 60 a series of holes J' at the right-hand end, through which the products of combustion pass to the external air.

With boilers of the flash type water has to be continuously forced into the water-space 65 at a relatively high pressure and at some point between the ends thereof is flashed into steam, and from that point on the steam becomes superheated to a greater or less degree. Boilers of this type are preferably operated 70 at high pressures varying, for example, from four hundred to five hundred pounds, and when so operated a considerable difference in temperature exists between the steam and any body of water which may be forced through 75 the water-space.

My invention depends for its operation upon the temperature difference existing between the steam and water, as distinguished from those thermo-regulators wherein the regulation is accomplished by changes in steam temperatures only. It sometimes happens that water under certain conditions works its way through the boiler tube or passage either as a plug or as a continuous stream. When regulators of the ordinary pressure type designed to regulate the supply of fuel to the burner are employed, the water being under high pressure acts in a manner similar to steam, and consequently tends to reduce the supply 85 of fuel at the very instant when it should be increased, and vice versa. I propose to overcome this objection by providing a thermostat, which thermostat is located in the boiler in such manner that it is acted upon by the 90 passage of steam or water, or both, in a manner to regulate the supply of fuel. As shown, the thermostat is located near the point where

the steam leaves the boiler; but, if desired, it can be located at some point more remote from the end. Near the delivery end of the boiler is a large opening K, and located there-
5 in and in direct contact with the steam or wa-
ter, or both, as they pass to the outlet-pipe Y is a thermostat L, the specific construction of which will be hereinafter described. For the present it is sufficient to say it is so arranged
10 so that it controls the opening and closing of the air-pressure valves U and V.

The auxiliary burner I consists of a tube having a plurality of openings through which the vapor escapes. Surrounding the burner
15 and provided with openings G² is a casing G', made of fire-brick or other similar material, and from this casing the products of combustion pass through the openings G² into the main combustion-chamber. By reason of the
20 casing G' being open on the lower side sufficient air is admitted at all times to maintain complete combustion, and the openings G² therein permit the flame to enter the main chamber N and heat the boiler and also the
25 vaporizer O. As shown, the vaporizer consists of a cylindrical tank, which communicates with the fuel-tank Q by means of a pipe O'. The auxiliary flame can be adjusted by the hand-operated valve I' and is not affected
30 by the automatic regulator, so that no matter what the condition of the main flame may be there is always heat enough developed by it to keep the vaporizer O in operative condition.

35 The main burner consists of a closed-end cylinder having a series of projecting nozzles H', each nozzle being provided with a single opening. Opposite each nozzle and provided with a suitable stuffing-box is a pressed plun-
40 ger H². The plungers act as cleaners for holes in the nozzles and are normally retained in the outward position by the compression-springs, as is indicated in Fig. 3. When it is desired to clean any one of the holes, its
45 plunger is forced inwardly, and as soon as the pressure is relieved therefrom it returns to the inoperative position. That portion of the casing G which is located directly under the main burner is provided with a series of
50 small holes G³ for admitting air to the main casing for supporting combustion. The cas-
ing being made of refractory and somewhat porous material and provided with air-admitting openings, the apparatus may be started
55 into operation by flooding the bottom of the casing with oil from the main burner H and then causing it to ignite, or separate starting means may be employed. When this is done, the flame will heat the vaporizer O until va-
60 por is formed therein, and the flow of oil will cease. The method described for vaporizing oil for starting may or may not be worked in conjunction with the auxiliary burner.

65 In order to change the direction of the

flame—as, for example, when it is desired to increase or decrease the flame which strikes the vaporizer O—the burner is mounted for oscillating movement in the ends of a U-shaped pipe P. The ends of the cylindrical support 70 for the burner-nozzles are closed around the pipe and suitable means are provided for preventing the escape of vapor. Secured to one end of the cylinder is an arm H³, whereby the position of the nozzles may be changed 75 either directly or through some system of levers.

The vaporizer O consists of a hollow cylindrical body, which extends across the casing in front of the flames and may or may not be 80 filled with asbestos or some such material for aiding in the vaporization of the fuel. One end of the vaporizer is connected by a pipe O' with the oil-tank Q, while connected to the bottom thereof is a pipe O², that unites 85 with the pipe P, leading to the main burner, and also with the pipe I², leading to the auxiliary burner. The passage of vapor to the main burner H is controlled by means of the valve P', actuated by a lever P², Fig. 2, which 90 lever is connected to the piston S. The pis-
ton is mounted within a cylinder S' and is, when not opposed by the air-pressure in the pipe R and cylinder, moved to the extreme 95 left under the action of the coil compression-spring S². Oil is supplied to the vaporizer from the tank Q, where it is maintained under a practically constant air-pressure received from the pipe R. The pressure in the pipe R is maintained by a pump or other suitable means. (Not shown.) With the valve 100 P' fully opened the fuel system is capable of furnishing the maximum amount of vapor necessary for any load for which the apparatus is designed.

105 The thermostat is made up of two pieces of dissimilar metal, such as brass and iron or copper and iron, and these pieces are riveted together and are held in place within the receptacle K of the boiler by a clamp K' at the upper end. The lower ends are connected to the shaft T, which passes through a stuffing-box in the plate T', that closes the bottom of the boiler-opening K. The opening K is in direct communication with the passage in the 110 boiler, and the thermostat is therefore in a position to instantly receive the benefit of any change in temperature either due to steam or water or a combination of both. The valves U and V are operated by an arm 115 T², which extends between their stems, a cer-
tain amount of lost motion being provided. The valves U and V close as soon as the arm moves away from the stems, due to the air-pressure. Each valve is provided with a 120 proper seat, and the valve V is arranged to exhaust into the open air. The valve U is connected to the pressure-pipe R and controls the passage of fluid through the pipe R' to the 125 cylinder, while the valve V is connected to the 130

pipe S^2 , which is also connected to the cylinder S' .

The action of my invention is as follows: Assuming that the boiler is hot and that a suitable supply of water is forced into it from the inlet-pipe W , the flame in the auxiliary burner is maintained constant, due to the air-pressure on the fuel-tank. The vaporizer O is heated to a certain temperature and supplies vapor to the main burner. The rise of temperature above a certain point has its effect on the thermostat L , and it slowly unwinds and in doing so presses the stem of valve U to the left, and air-pressure is admitted to the pipe R' . This insures the closing of the exhaust-valve V , and the air-pressure forces the piston S against the action of the coil-spring S^3 and decreases the opening in the fuel-controlling valve P' to the proper point.

Assuming that for any cause the temperature of the steam drops below a predetermined point—such, for example, as would take place when water passes through the boiler in the form of a plug or stream—the arm T of the thermostat will move in a clockwise direction, thereby relieving the pressure-valve U and permitting it to shut, at the same time opening the exhaust-valve V and exhausting the air from the cylinder S' and the pipes R' and S^2 . As soon as this is done the coiled compression-spring S^3 will open the fuel-valve P' and permit an amount of fuel to flow to the main burner which may vary from minimum to maximum in accordance with the demand.

Between the ends of the two valve-stems is a dead-space, wherein the arm T is out of engagement, and when the apparatus is operating under normal conditions the arm will occupy this dead-space more or less of the time. The opening of the valves will generally be very slight.

By constructing and arranging the parts as shown I provide a regulator for flash-boilers working with superheated steam which is very sensitive, and when for any reason water passes through the tube or passage in the boiler without being converted into steam it will quickly reduce the temperature of the thermostat, and the latter will cause an increase in the fuel-supply. With this arrangement the regulation takes place immediately, for the controlling means is located directly in the path of the outgoing steam or water, and any change in temperature is instantly detected and compensated for.

What I claim as new, and desire to secure by Letters Patent of the United States, is—

1. In a combination, a boiler, a casing therefor containing a main fire-chamber, a main burner therein, an auxiliary fire-casing having perforations by which it communicates with the main chamber, an auxiliary burner in said auxiliary casing, the flame from which passes through said perforations and unites with the flame from the main burner to heat the boiler,

and a vaporizer located between the auxiliary casing and the main burner so that it is acted upon by the flames from both burners.

2. In a combination, a boiler, a casing therefor containing a main fire-chamber, a main burner therein, an auxiliary fire-casing open to the atmosphere and extending into the main chamber and having perforations by which it communicates with said main chamber, an auxiliary burner in said auxiliary casing, and a vaporizer located between the auxiliary casing and the main burner, and connected with both burners.

3. In combination, a boiler, a burner having a plurality of nozzles, a means for simultaneously adjusting all of the nozzles to change their effect on the vaporizer, an auxiliary burner, a casing for the auxiliary burner, a vaporizer situated between the main and auxiliary burners, and a casing for the burners and boiler which is provided with an opening for discharging products of combustion.

4. In combination, a casing, a boiler mounted in one end thereof, a chamber which is situated between the boiler and the end of the casing, a burner mounted in the end of the casing opposite the boiler and chamber, a vaporizer situated between the burner and the boiler, and a flue or chimney which connects with the chamber and extends back over the casing substantially parallel therewith.

5. In combination, a casing, a boiler mounted therein, a chamber which is situated between the boiler and the end of the casing, a main burner which is mounted in the opposite end of the casing, a vaporizer situated between the burner and the boiler, an auxiliary burner which is situated between the boiler and the vaporizer so that the flame therefrom will heat the vaporizer and also the boiler, and a flue which connects with the chamber and extends back over the casing toward the main burner.

6. In combination, a boiler, a casing therefor, a burner located in one end of the casing, a vaporizer located between the boiler and burner, a chamber which is situated between the boiler and the other end of the casing, and a flaring funnel which connects with the chamber and extends back over the casing toward the burner.

7. In combination, a boiler, a casing in which the boiler is located at one end, a burner located within the casing and at the end opposite the boiler, a chamber situated between the end of the casing and the boiler and away from the burner, a baffling means for directing the flames through flue-spaces in the boiler, and a flue which communicates with the chamber and conveys the products of combustion over the boiler toward the burner.

8. In combination, a boiler, projections formed thereon for baffling the flames, a main burner, a second baffling device for directing the flames from the main burner toward said

projections, an auxiliary burner which is constantly in operation, a casing for the boiler and burners, a chamber in the casing which receives the products of combustion after they 5 impart heat to the boiler, and a flue which opens into the said chamber.

9. In combination, a boiler, a burner, an auxiliary burner, a casing for the auxiliary burner which is open to the atmosphere, a vaporizer which is acted upon by both burners, and a casing for the burner and boiler which 10 is also open to the atmosphere at a point adjacent to the burner and is provided with an orifice for discharging the products of combustion. 15

10. In combination, a boiler, a casing therefore, a main burner situated at one end of the casing and comprising a plurality of nozzles which discharge unmixed vapor, an auxiliary burner situated between the main burner and the boiler and in line therewith, and a vaporizer situated between the main and auxiliary burners so that it is affected by the flames from both. 20

In witness whereof I have hereunto set my hand this 18th day of June, 1901.

ELIHU THOMSON.
